COMBINED ELECTROMAGNETIC REGULATOR AND SWITCH

Friedrich Menzel, Stuttgart, Germany; vested
in the Alien Property CustodianApplication March 10, 1942, Serial No. 434,042
In Germany May 6, 1940

5 Claims. (Cl. 320—33)

The invention relates to combined electromagnetic regulator and switches for controlling electric circuits, and more particularly adapted for use in connection with battery-charging generators especially on vehicles.

In order to obtain a good utilization of the magnet core for three armatures a transverse piece is arranged, according to the invention, on the magnet core so that the one part of the magnet core influences one of the armatures, the other part of the magnet core the second armature and the whole magnet core the third armature. The advantage is hereby attained to obtain three different paths of the magnetic flux of which one can be used for a voltage regulator, the second for a current regulator or for a control regulator and the third for a charging switch.

Two embodiments of the invention are illustrated by way of example in the accompanying drawing, in which

Fig. 1 shows a regulator switch arrangement with a voltage coil and a current coil;

Fig. 2 a regulator switch arrangement with a voltage coil, a current coil and an auxiliary coil and

Fig. 3 is a detail view showing a modification of the circuit arrangement shown in Fig. 2.

The regulator switch arrangement shown in Fig. 1 comprises a magnet core 1 with a pressure coil 2 and a current coil 3, between which a transverse piece 4 is mounted on the magnet core 1. The magnet core 1 is arranged on a base plate 5 of a magnet frame 5, 6, 7, on the upwardly extending arm 6 of which an armature 8 is suspended. The transverse piece 4 is equipped with an upwardly extending arm 9 on the end of which an insulated armature 10 suspended. On the arm 9 of the transverse piece 4 an armature 11 is suspended insulated. The two armatures 10 and 11 are connected by a wiring 12.

The armature 8 belongs to its automatic charging switch and carries a contact spring 13, the contact 14 of said spring co-operating with a contact 15. The contact 15 is connected to a battery 16. The armature 10 belongs to a voltage regulator and carries a contact spring 17, the contact 18 of which co-operates with a contact 19 which is grounded. The armature 11 belongs to a current regulator and carries a contact 20, which co-operates with a contact 21. A dynamo 22 has a field winding 23 and a field resistance 24, between which the wire 25 is connected which leads to the contact 21.

The line of force flux of the charging switch extends through the whole magnet core 1, the

right hand half of the base plate 5, the arm 6 and the armature 8. The line of force flux of the voltage regulator extends through the upper part of the magnet core 1, the transverse piece 4, the arm 9 and the armature 10. The line of force flux of the current regulator extends through the lower part of the magnet core 1, the left hand half of the base plate 5, the extension piece 7 of the magnet frame and the armature 11. The line of force fluxes of the voltage regulator and of the current regulator use both the transverse piece 4 without impairing thereby the operation of the two regulators.

In the switched position shown in the drawing 15 the field resistance 24 is short-circuited by the following connection: wire 25, pair of contacts 21, 20, armature 11, wire 12, armature 10, pair of contacts 18, 19, ground. When the dynamo 22 produces sufficient voltage, the armature 8 is attracted and closes the pair of contacts 14, 15, whereby the following circuit is closed: ground, dynamo 22, current coil 3, magnet frame 5, 6, armature 8, contact spring 13, pair of contacts, 14, 15, battery 16, ground. The battery 16 is charged from the dynamo 22. If at low number 20 of revolutions of the dynamo 22 a return current flows from the battery 16 to the dynamo 22, the charging switch opens its pair of contacts 14, 15 under the influence of the return current flowing 25 through the current coil 3.

If after the closing of the charging switch, the voltage produced by the dynamo 22 rises to beyond a certain amount, the armature 10 is attracted under the influence of the voltage coil 3 and opens the pair of contacts 18, 19. The resistance 24 becomes thereby effective in the circuit of the field winding 23. The voltage regulator begins to regulate to uniform voltage by periodical switching-in and cutting-out of the field 30 resistance 24.

At a predetermined current intensity the armature 11 is attracted under the influence of the current coil 3 and opens the pair of contacts 20, 21. Thereby the resistance 24 in the circuit of 35 the field winding 23 becomes also effective. The current regulator regulates by periodical switching-in and cutting-out of the field resistance 24 to rapidly decreasing voltage of the dynamo 22, so that an overloading of the dynamo 22 by high 40 discharge of current is prevented.

As can be seen from the drawing the transverse piece 4 with the extension arm 9 and the magnet frame 5, 6 are of L-shape, the magnet core 1 being arranged as well perpendicularly to the transverse piece 4 as also to the base plate 5.

The two armatures 8 and 10 of for instance rectangular form are arranged at the ends of the upwardly extending arms 6 and 9 and one arm of each of the armatures extends by one half over the attracting surface of the magnet core 1. One arm of the armature 11, which is for instance also of rectangular shape, extends approximately parallel to the transverse piece 4 and its other arm is opposite to the attracting surface of the magnet frame formed by the extension piece 7. The construction of the magnet frame 5, 6, 7 and the arrangement of the three armatures 8, 10 and 11 enable a compact construction of the two regulators and of the charging switch. On the magnet core 1 only two coils 2 and 3 are arranged which influence the voltage regulator, the current regulator and the charging switch in a practical manner.

The regulator switching arrangement shown in Fig. 2 is essentially of the same construction as the arrangement shown in Fig. 1 and differs chiefly by the arrangement of another coil on the magnet core and by a different manner of operation of the two regulators.

On the part of the magnet core 1 co-ordinated to the voltage regulator and situated above the transverse piece 4 there is arranged, besides the voltage coil 2, a current coil 26. The armature 11, which in this instance is not suspended insulated comprises a contact 27 which cooperates with a contact 28, to which one of the ends of the current coil 26 is connected. The armature 11 controls the current coil 26 and forms consequently a control regulator. The armature 10 of the voltage regulator, suspended insulated, is connected to a wire 29 branching off between the field winding 23 and the field resistance 24. The contact 18 on the armature 10 of the voltage regulator can oscillate between the contact 19 and a contact 30 mounted on the arm 9 of the transverse piece 4. The purpose of the contact 30 is to short circuit the field winding of the generator.

The armature 10 of the voltage regulator regulates the voltage of the dynamo by periodical switching-in and short-circuiting of the field resistance 24 or by periodical short-circuiting and switching-in of the field winding 23. Up to a certain current intensity it is regulated to uniform voltage. When this certain current is exceeded, the armature 11 of the control regulator is attracted under the influence of the current coil 3 and closes the pair of contacts 27, 28, whereby the current coil 26 is switched parallel to the current coil 3. The voltage regulator is then influenced as well by the voltage coil 2 as also by the current coil 26 and consequently regulates then the dynamo 22 to decreasing voltage. The dynamo 22 is thus protected against stressing by too high current delivery. At high currents the voltage of the dynamo 22 does not drop so rapidly owing to this regulation as it is the case in the arrangement shown in Fig. 1, so that the dynamo is better utilized.

Instead of the current coil 26 a voltage coil may be provided on the upper part of the magnet core, this voltage coil being arranged parallel to the voltage coil 2 and the circuit of the same is switched-in and cut-out by the contacts 27, 28 of the control regulator. Thus in Fig. 3 the armature 11 may be insulated from the magnet frame and connected to ground at 30 and when operated will connect voltage coil 26 to ground.

I claim:

1. The combination of a variable speed generator and a storage battery to be charged there-

by, said generator having a shunt field and a regulating resistance connected thereto, of an electromagnetic structure comprising a core, a cross piece of magnetic material intermediate the ends of said core, a voltage coil on said core at one side of said piece and connected across said generator, a normally open circuited series coil wound on said core at the said one side of said cross piece, a second series coil wound on said core at the opposite side of said cross piece, a magnetic frame secured to one end of said core and extending substantially the length thereof, an armature supported on said frame and movable in response to the total flux through said core to close the circuit from said generator to said battery, said cross piece having an extension along said core on said one side, an armature carried by said extension, normally short circuiting said resistance and operable by the flux in the core at said one side to connect said resistance in circuit in series with said field, and an armature operable in response to the flux in said core at said opposite side to close the circuit through said normally open circuited series coil on said one side in parallel to the circuit through said series coil on said opposite side, said coils being wound and connected in such a way that their respective currents create fluxes which are additive when said battery is charging.

2. The combination of a variable speed generator and a storage battery to be charged thereby, said generator having a shunt field and a regulating resistance connected thereto, of an electromagnetic structure comprising a core, a cross piece of magnetic material intermediate the ends of said core, a voltage coil on said core at one side of said piece and connected across said generator, a normally open circuited coil wound on said core at the said one side of said cross piece, a series coil wound on said core at the opposite side of said cross piece, a magnetic frame secured to one end of said core and extending substantially the length thereof, an armature supported on said frame and movable in response to the total flux through said core to close the circuit from said generator to said battery, said cross piece having an extension along said core on said one side, an armature carried by said extension, normally short circuiting said resistance and operable by the flux in the core at said one side to connect said resistance in circuit in series with said field, and an armature operable in response to the flux in said core at said opposite side to close the circuit through said normally open circuited coil on said one side, said coils being wound and connected in such a way that their respective currents create fluxes which are additive when said battery is charging.

3. The apparatus claimed in claim 1 wherein contacts and connections are provided whereby on release of the armature mounted on said cross piece the field of said generator is short circuited.

4. The apparatus claimed in claim 1 wherein the frame, the cross piece and the armatures are L-shaped, each having portions extending along said core and a portion normal to the core axis and such elements together form a substantially rectangular box like structure enclosing the coils.

5. The combination of a variable speed generator and a storage battery to be charged thereby, said generator having a shunt field and a regulating resistance connected thereto, of an electromagnetic structure comprising a core, a cross piece of magnetic material intermediate the ends of the core, a voltage coil on said core at one side

of said piece and connected across said generator, a normally open circuited coil on said core on the said one side, a series coil wound on said core on the other side of said cross piece, a magnet frame secured to said core, an armature supported on said frame and movable in response to the total flux through said core to close the circuit from said generator to said battery, an armature carried by said frame, normally short circuiting said resistance and operable by the flux in said core at

10

said one side to connect said resistance in series with said field, and an armature operable in response to the flux in said core at said opposite side to close the circuit through said normally open circuited coil, said coils on said one side being wound and connected in such a way that their respective currents create fluxes which are additive when the battery is charging.
